PARK A. NUTTALL, OF YOUNGSTOWN, OHIO, ASSIGNOR TO TRUSCON STEEL COMPANY, OF YOUNGSTOWN, OHIO, A CORPORATION OF MICHIGAN.

SAND-RETAINING BAR FOR FOUNDRY FLASKS.

Application filed February 4, 1927. Serial No. 165,966.

This invention relates to an improved foundry accessory, and more particularly to a novel sand retaining bar for foundry flasks.

To that end the invention contemplates a bar or strip of metal having special features and characteristics for retaining or holding the sand in the flask during the handling thereof in carrying out the molding operations. While it has been heretofore the common practice to use plain bars or strips for this purpose, and in some cases to use bars having portions formed to provide sand engaging shoulders; or to use perforated bars for receiving nails, pins or the like which are embedded in the sand, nevertheless, it is desirable to provide a bar which not only possesses structural features which effectively hold the sand, throughout the length of the flask, but which also provides a point of fastening for the interior or cross bars of the flask.

Accordingly, a more specific object of the invention is to provide a main or primary sand retaining bar having a portion thereof corrugated in such a way that all of the sand substantially above half the depth of the cope or part of the flask in which the bar is used, is held in such a way that it will not drop out when the flask is lifted. That is to say, the present invention contemplates a bar having portions which present relatively opposite inclined walls at one edge thereof and which cooperate with the inclined sides of the mold part in such a way that the body of the sand between said part and the bar is engaged by oppositely inclined convergently related walls.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings in which:

Figure 1 is a top plan view of a foundry flask having the improved sand retaining bar therein.

Figure 2 is a side elevation partly in section illustrating the present improvements.

Figure 3 is an enlarged detail perspective view of a portion of the improved sand retaining bar.

Figures 4 and 5 are respectively vertical sectional views taken on the lines 4—4 and 5—5 of Figure 1.

Figure 6 is a vertical transverse sectional view taken on the line 6—6 of Figure 1.

Similar reference characters designate corresponding parts throughout the several figures of the drawings.

In carrying out the present invention, it is proposed to use the same in connection with the cope F of a foundry flask, the same including a rectangular cope having the opposite side walls 1 and the end walls 2, the said walls being bowed or bent outwardly at their medial portions to provide the divergent portions x and y thereby to provide a side retaining groove z at the inside of the frame.

The sand retaining bar constituting the present invention is designated generally as A and is intended to be placed in the flask, longitudinally, between the opposite side walls 1—1 of the cope so that the ends thereof may be anchored in any suitable manner, as by welding to the end walls 2—2. The said bar A preferably consists of a body portion of suitable length and width, substantially one-half of the width thereof being of plain formation while the opposite half is corrugated to provide oppositely inclined and oppositely disposed smooth sandkeying shoulders 4 and 5. This arrangement provides one side of the bar with a plain edge 6, while the opposite edge is of sinuous formation as clearly shown in Figures 1 and 3. The shoulders 4 and 5, as previously indicated are formed at opposite faces of the body of the bar thereby to provide a multiplicity of keying elements along one edge and at opposite faces of the bar. It will also be observed that each shoulder is inclined with respect to the flat portion 3 of the bar so that an over-hanging effect is produced by the shoulders with reference to the flat portion of the bar whereby the shoulders cooperate with the inclined faces x of the cope to provide a pocket or restricted facing for retaining the sand in place.

The said retaining bar A also constitutes a retaining means for the interior bars B which are arranged in spaced relation between the sides 1—1 of the cope and the bar A to assist in holding the sand. The bars B may be secured in position, that is, to the sides of the cope and the bar A, by welding or otherwise

and not only serve to strengthen and reinforce the cope but also greatly assist in retaining the sand during the handling of the mold. This is a particularly advantageous feature since in large flasks, the pressure on the sand during the pounding and casting operation is likely to distort or bend the sides of the cope, but this action is effectually resisted by the present arrangement. The 5 position of the main retaining bar with its corrugated edge and the interior bars B also serves to prevent the sand in the cope portion of the flask from sinking down, when the same is turned on end to receive the molten metal, thereby insuring proper registration of the two halves of the mold.

From the foregoing, it will be apparent that the present invention provides a simple and practical retaining bar which not only 20 possesses the necessary structural features to retain the sand from slipping out of the flask when lifted around, but also makes it easy to knock the sand out when it is desired to do so. Furthermore, this arrangement avoids the 25 use of a bar having openings or struck-out portions of metal which present rough or sharp edges likely to injure the hands of the workmen in handling the same, and also cause too much sand adherence when the mold is to 30 be cleared.

Without further description it is thought that the features and advantages of the invention will be readily apparent to those skilled in the art, and it will of course be understood that changes in the form, proportion 35 and minor details of construction may be resorted to, without departing from the spirit

of the invention and scope of the appended claims.

I claim:—

1. A sand retaining bar for foundry flasks comprising a metallic body having a continuous sinuous edge formed by alternate oppositely inclined connecting shoulders extending from the medial portion of the body of the bar, which body is flat at the side opposite the said connecting shoulders, and means for connecting the ends of the bar to the body of the flask. 40

2. A sand retaining bar for foundry flasks comprising a metallic body having a flat portion and a continuous corrugated sand holding portion adjoining the same and extending from the medial portion to the edge of the bar thereby providing a plurality of connected oppositely inclined sand holding shoulders, and means for connecting the ends of the bar to the body of the flask. 50

3. A sand retaining bar for foundry flasks comprising a metallic strip-like body having a flat portion and being corrugated from one edge toward said flat portion thereby to provide a plurality of smooth alternately inclined integrally connected sand keying shoulders arranged at opposite sides of the plane of the flat portion of the body and forming a continuous sand keying edge adapted to be located in the plane of the edge of the flask, and a weld connecting opposite ends of the bar to the body of the flask. 60

In testimony whereof I hereunto affix my signature.

PARK A. NUTTALL.
